UNITED STATES PATENT OFFICE.

ALONZO G. REYNOLDS, OF SAN FRANCISCO, CALIFORNIA.

CONCRETE WALL CONSTRUCTION.

Application filed October 4, 1924. Serial No. 741,710.

To all whom it may concern:

Be it known that I, ALONZO G. REYNOLDS, a citizen of the United States, residing at San Francisco, in the county of San Francisco and State of California, have invented new and useful Improvements in Concrete Wall Constructions, of which the following is a specification.

This invention relates to concrete slabs 10 for walls and has particular reference to the construction of a concrete wall out of slabs adapted to be superimposed one upon the other and further to space two walls thus constructed so as to provide an air space 15 therebetween.

Another object is to provide means for securing the slabs together previous to pouring the binding cement which forms the column.

20 A still further object is to provide means whereby a form is automatically constructed thus removing the necessity of a wood form for confining plastic concrete as is now commonly needed.

25 Other objects and advantages will be apparent during the course of the following description.

In the accompanying drawings forming a part of this specification, and in which like 30 numerals are employed to designate like parts throughout the same,

Figure 1 is a cross section of a wall constructed in accordance with my invention, and

35 Figure 2 is a fragmentary perspective view of two of my slabs as they appear previous to being placed in a wall.

In the building of concrete walls, it is now customary to build forms, lay re-enforcing bars in these forms, then pour concrete therearound to make a monolithic structure. This construction is expensive owing to the large amount of lumber which must be employed. Furthermore, the erection 40 of the forms requires considerable time and labor.

I have formed slabs as designated by the 50 numeral 5, which slabs are cast in suitable molds and have re-enforcing rods 6 cast therein. The ends of these rods protrude at an angle from a point on one side of the block and near the end thereof. These protruding ends are designated by the numeral 7.

55 It is preferable to form a tongue 8 along

one edge of the slabs so as to form an interlock between the next slab above, which is provided with a suitable groove. The ends of the slabs are fashioned in the same manner, one of the grooves being shown at 9. 60 At the same time that I cast the slabs I insert near each end thereof, a sheet metal member 11. This sheet metal member has one end split and bent as shown in dotted lines in Figure 2, as indicated by the numeral 12.

These bent ends serve to secure the sheet metal members in the concrete when the same is poured. In each of these sheet metal members is provided securing slots 13, 70 through which bolts 14 are adapted to be placed. This construction completes the forming of a slab.

When the blocks thus formed are set in a wall, the result is that the sheet metal members lie parallel with each other and the ends 7 of the re-enforcing rods cross each other. It is to be understood that a second set of slabs are placed parallel to the first set and in such a manner that the sheet metal members contact the sheet metal members of the first row of slabs. This will also cause the ends 7 of the second set to cross each other and at the same time lie in close proximity to the cross re-enforcing bars of the first set of 80 slabs.

When the slabs are thus set up, bolts 14 are passed through the slots 13 of the contacting metal members 11 and tightened so as to hold the slabs in proper relation to each other, after which the concrete 17 is poured into the form thus constructed by the ends of the slabs and the sheet metal members. This concrete, upon hardening, forms an absolute lock around the crossed 90 ends 7 of the different slabs and at the same time forms a column, which gives the wall considerable strength.

It will thus be seen that I have provided a very simple and efficient slab out of which a wall may be constructed in a minimum amount of time.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, I claim:—

1. In a concrete slab of rectangular shape, a plurality of re-enforcing bars embedded in said slab and having the ends protruding therefrom on one side of said slab and near the ends thereof, said protruding ends being diverging from each other, and a sheet metal member positioned in said slab near each end thereof so as to form parallel extensions at right angles to the surface of said slabs.

2. A wall construction comprising a plurality of slabs; re-enforcing bars positioned in said slabs, similar re-enforcing bars in the other of said slabs with which said slab is to be associated, a sheet metal member secured near each end of each slab and extending at right angles to the face thereof, and means for securing said sheet metal members of said slabs one to the other. 15 20

In testimony whereof I affix my signature.

ALONZO G. REYNOLDS.
